UNITED STATES PATENT OFFICE.

ALFRED H. HUMPHREY, OF NEW YORK, N. Y.

GAS-LAMP.

No. 878,397.

Specification of Letters Patent.

Patented Feb. 4, 1908.

Application filed June 22, 1906. Serial No. 322,891.

To all whom it may concern:

Be it known that I, ALFRED H. HUMPHREY, a citizen of the United States, residing at New York, borough of Manhattan, and 5 State of New York, have invented certain new and useful Improvements in Gas-Lamps, of which the following is a specification.

This invention relates to improvements in 10 gas lamps.

The objects of this invention are, first, to provide an improved gas lamp having inverted burners, in which all of the parts are accessible, so that it is not necessary to disassemble the lamp for the purpose of adjusting or arranging the parts. Second, to provide in a gas lamp having inverted burners, an improved construction and arrangement of the main burner and the pilot light valves. 15 Third, to provide in a gas lamp an improved valve construction. Fourth, to provide in a gas lamp an improved flash pilot valve. Fifth, to provide in a gas lamp an improved construction of burner.

20 Further objects, and objects relating to structural details, will definitely appear from the detailed description to follow.

I accomplish the objects of my invention by the devices and means described in the 25 following specification.

The invention is clearly defined and pointed out in the claims.

A structure embodying the features of my invention is clearly illustrated in the accompanying drawings forming a part of this 30 specification, in which—

Figure 1 is a vertical section of my improved gas lamp, portions being shown in full lines to better show their construction. 40 Fig. 2 is an enlarged detail elevation of the gas valves, looking from the left of Fig. 1. Fig. 3 is an enlarged section through the valves, taken on a line corresponding to line 3-3 of Fig. 2. Fig. 4 is an enlarged detail 45 section showing the means for supporting the chimney, taken on a line corresponding to line 4-4 of Fig. 1. Fig. 5 is an enlarged detail section taken on a line corresponding to line 5-5 of Fig. 1, showing the means for 50 securing the globe in its closed position. Fig. 6 is an enlarged detail showing the pilot valve in its open or flashing position. Fig. 55 7 is an enlarged detail section taken on a line corresponding to line 7-7 of Fig. 1, showing the construction of the burner and the relation of these parts.

In the drawings the sectional views are taken looking in the direction of the little arrows at the ends of the section lines, and similar letters of reference refer to similar 60 parts throughout the several views.

Referring to the drawings, the chimney A is preferably provided at its lower end with an outwardly projecting flange A' having a downwardly turned rim A'' thereon. The 65 chimney A is preferably supported by the gas delivery pipe B, the same being provided with a T-coupling from which depend the gas delivery pipe B' and the dummy B''. The chimney is adjustably secured upon the pipe 70 B' by means of the adjustable collars a' which engage the clips a projecting from the chimney.

The valve casing C is connected to the lower end of the delivery pipe B'. (See Fig. 75 1.) The valve casing C is provided with passages L, M and N, which connect the delivery pipe B' to the pipe D which delivers to the gas delivery ring D'. The chimney A is arranged through the gas delivery ring D' and 80 the burners S are connected thereto. The passage M is controlled by the valve C'. (See Fig. 3.) This valve is a rotary valve and is provided with two ports c' arranged to be alternately brought into position for opening 85 the valve.

On the projecting end or stem of the valve C' I pivot the operating lever H. This lever is provided with a pawl I' adapted to engage the ratchet wheel I which is secured to the 90 valve stem. The ratchet I is, in the structure illustrated, provided with four teeth, so that each stroke of the lever gives the valve a quarter turn. As the valve is provided with two ports, it is evident that each stroke 95 of the lever opens or closes the valve. The lever is provided with a projecting stop h'' which engages the stop h on the valve casing to limit the down-stroke thereof.

A spring dog i projects outwardly from the 100 valve casing to prevent the return of the ratchet. The lever is returned to its initial position by the spring H', which is connected to the outer end thereof, and to the connecting stop pin h on the valve casing. A depending chain, as H'', is preferably provided for operating the lever H. An indicator J is secured to the outer end of the valve stem to indicate whether the valve is in its open or closed position, the main burner valves 105 in the drawing being shown in their open position.

The operating lever K of the pilot-light is arranged to move in the same direction as the lever H. The lever H is provided with a projecting pin h' adapted to engage the lever K 5 when the lever H has partially completed its stroke, to open the pilot-valve, the valve-levers being shown at the end of their stroke by dotted lines in Fig. 2.

The delivery of gas to the pilot L' from the 10 passage L is controlled by the valve O. This valve is threaded into a cup-like casing P, which is in turn threaded into the main valve casing C. The casing P is provided with the passage p through its inner end, and a passage p' through one side thereof. This passage opens into an annular passage p'' about the valve casing, which registers with the pilot-light tube.

The valve O is provided with a port o 20 which is always open to supply the pilot. The delivery of gas through this port is controlled by the adjusting screw q which is threaded into the valve O from its outer end. This enables the accurate adjustment of the port 25 to regulate the normal flow of gas to the pilot.

When the lever K is operated, the valve O is drawn from its seat on the inner end of the casing P, allowing a supply of gas to pass 30 to the pilot for flashing the same. As soon as the lever H is released, it is returned to its initial position, as stated, by the spring H'. A spring K' is provided for returning the pilot valve to its initial position, so that the 35 pilot valve is automatically closed when the lever H is released. The levers H and K are so arranged that the main valve is opened before the pilot is flashed, allowing the gas to drive the air from the burners and pipes 40 beyond the valve. When it is desired to cut off the gas or turn out the lights, it is only necessary to again pull on the operating chain.

The burner tubes are arranged through the 45 outwardly projecting flange A' of the chimney, so that their tips s are below the same. The burner tubes S are threaded upon the nipples d carried by the gas delivery ring D'. The burner tubes S are provided with air inlets s' at their upper end, of sufficient size to 50 allow the nozzles T to be inserted and manipulated therethrough. The nozzles T are threaded upon the nipples d independently of the burner tubes, so that they may be 55 placed in position or removed without in anywise disturbing the tubes,—the arrangement clearly appearing in Figs. 1 and 7, the same being shown in detail in the latter figure.

The air openings s' are provided with 60 shutter-valves S' which are threaded thereon and adapted to be adjusted to regulate the size of the opening and to render the nozzles T accessible. Needle valves t are provided for adjusting the opening of the nozzle. By 65 thus forming and arranging the parts, the

nozzles may be readily removed when it is desired to change or replace the same or clean them, without disturbing the other parts of the burner. This is of very great advantage, particularly with the inverted 70 burner construction.

The outer casing G is made vertically adjustable to afford access to these parts, the casing being indicated by dotted lines in its elevated position. The top G' of the casing 75 is slidably mounted upon the pipe B. In the construction illustrated, it is not connected to the casing G, but it is evident that this might be done if desired. When the casing is in its lower position, it rests on the 80 outwardly projecting flange G''' of the band G'', which forms the base of the casing.

The casing is slotted at one side to receive the valve C, so that the valve projects outside thereof. An adjustable rest b' is provided for the casing when in its elevated position, as is indicated by dotted lines in Fig. 1. This rest is mounted upon the collar b arranged on the gas delivery pipe B', so that it may be swung out to the position indicated 90 by dotted lines in Fig. 1, or swung inwardly within the casing to allow the same to drop down onto the band G'.

The globe F' is carried by the globe ring F, which is hinged to an ear f on the valve so 95 that it may be swung down as indicated by dotted lines in Fig. 1. The globe is held in its closed position by the thumb-nut g', which engages a suitable slot in the arm g. (See Figs. 1 and 5.)

By arranging the valve C in the position illustrated, the same is conveniently operated, and is so arranged as not to be materially heated by the lamp. This arrangement has the further advantage of serving as 105 a trap for any solids or condensation that might otherwise pass to the burners and clog the gas delivery nozzles or otherwise interfere with the proper operation of the burners. It is evident that with the burners arranged 110 in the inverted position, the tendency is for the heat to be delivered to the parts above. By arranging the chimney as I have illustrated and described, the heat is largely carried away thereby, and the parts of the 115 lamp are quite fully protected.

I have illustrated and described my improved lamp in detail in the form preferred by me on account of structural simplicity and economy, and convenience in adjusting and 120 care in use; I am, however, aware that it is capable of considerable variation in structural details without departing from my invention.

Having thus described my invention, what 125 I claim as new and desire to secure by Letters Patent is:

1. In a gas lamp, the combination with a gas delivery pipe of a chimney having an outwardly projecting flange at its lower end, 130

- secured to said delivery pipe; a valve casing at the lower end of said gas delivery pipe, projecting outwardly therefrom; a gas delivery ring through which said chimney is arranged, connected to said gas delivery pipe; 5 a plurality of inverted burners arranged through said flange on said chimney, connected to said gas delivery ring; a globe adapted to inclose the lower portion of said chimney; a depending ear on said valve, to which said globe is hinged; a casing band having an outwardly projecting flange at its upper end, arranged on said flange on said chimney; a vertically adjustable casing adapted to rest on said casing band, said casing having a slot therein adapted to receive 10 said valve casing; a rest for holding said casing in its elevated position, and a deflector plate, slidably arranged on said delivery pipe, co-acting for the purpose specified.
2. In a gas lamp, the combination with a gas delivery pipe of a chimney having an outwardly projecting flange at its lower end, secured to said delivery pipe; a valve casing 15 at the lower end of said gas delivery pipe, projecting outwardly therefrom; a gas delivery ring through which said chimney is arranged, connected to said gas delivery pipe; a plurality of inverted burners arranged 20 through said flange on said chimney connected to said gas delivery ring; a casing band having an outwardly projecting flange at its upper end, arranged on said flange on said chimney; a vertically adjustable casing 25 adapted to rest on said casing band, said casing having a slot therein adapted to receive said valve casing; a rest for holding said casing in its elevated position, and a deflector plate, slidably arranged on said delivery 30 pipe, co-acting for the purpose specified.
3. In a gas lamp, the combination with a gas delivery pipe of a chimney having an outwardly projecting flange at its lower end, secured to said delivery pipe; a valve casing 35 at the lower end of said gas delivery pipe, projecting outwardly therefrom; a gas delivery ring through which said chimney is arranged, connected to said gas delivery pipe; a plurality of inverted burners arranged 40 through said flange on said chimney connected to said gas delivery ring; a casing band having an outwardly projecting flange at its upper end, arranged on said flange on said chimney; a vertically adjustable casing 45 adapted to rest on said casing band, said casing having a slot therein adapted to receive said valve casing; a rest for holding said casing in its elevated position, and a deflector plate, slidably arranged on said delivery pipe, co-acting for the purpose specified.
4. In a gas lamp, the combination with a gas delivery pipe of a chimney having an outwardly projecting flange at its lower end, secured to said delivery pipe; a valve casing 50 at the lower end of said gas delivery pipe, projecting outwardly therefrom; a gas delivery ring through which said chimney is arranged, connected to said gas delivery pipe; a plurality of inverted burners arranged 55 through said flange on said chimney connected to said gas delivery ring; a casing band having an outwardly projecting flange at its upper end, arranged on said flange on said chimney; a vertically adjustable casing 60 adapted to rest on said casing band, said casing having a slot therein adapted to receive said valve casing, and a deflector plate, slidably arranged on said delivery pipe, co-acting for the purpose specified.
5. In a gas lamp, the combination with a gas delivery pipe of a chimney having an outwardly projecting flange at its lower end, secured to said delivery pipe; a valve casing 65 at the lower end of said gas delivery pipe, projecting outwardly therefrom; a gas delivery 70 ring through which said chimney is arranged, connected to said gas delivery pipe; a casing band having an outwardly projecting flange at its upper end, arranged on said flange on said chimney; a vertically adjustable casing 75 adapted to rest on said casing band, said casing having a slot therein adapted to receive said valve casing; a rest for holding said casing in its elevated position, co-acting for the purpose specified.
6. In a gas lamp, the combination with a gas delivery pipe of a chimney having an outwardly projecting flange at its lower end, secured to said delivery pipe; a valve casing 80 at the lower end of said gas delivery pipe, projecting outwardly therefrom; a gas delivery ring through which said chimney is arranged, connected to said gas delivery pipe; a plurality of inverted burners arranged 85 through said flange on said chimney connected to said gas delivery ring; a casing band having an outwardly projecting flange at its upper end, arranged on said flange on said chimney; a vertically adjustable casing 90 adapted to rest on said casing band, said casing having a slot therein adapted to receive said valve casing, co-acting for the purpose 95 specified.
7. In a gas lamp, the combination with a gas delivery pipe of a chimney having an outwardly projecting flange at its lower end, secured to said delivery pipe; a valve casing 100 at the lower end of said gas delivery pipe, projecting outwardly therefrom; a gas delivery ring through which said chimney is arranged, connected to said gas delivery pipe; a plurality of inverted burners arranged 105 through said flange on said chimney connected to said gas delivery ring; a vertically adjustable casing; a rest for holding said casing in its elevated position; and a deflector plate slidably arranged on said delivery pipe, 110 co-acting for the purpose specified.
8. In a gas lamp, the combination with a gas delivery pipe of a chimney having an outwardly projecting flange at its lower end, secured to said delivery pipe; a valve casing 115 at the lower end of said gas delivery pipe, projecting outwardly therefrom; a gas delivery ring through which said chimney is arranged, connected to said gas delivery pipe; a plurality of inverted burners arranged 120 through said flange on said chimney connected to said gas delivery ring; a vertically adjustable casing having a slot therein adapted to receive said valve; and a deflector plate, slidably arranged on said delivery pipe, 125 co-acting for the purpose specified.
9. In a gas lamp, the combination with a gas delivery pipe of a chimney having an outwardly projecting flange at its lower end, secured to said delivery pipe; a valve casing 130

at the lower end of said gas delivery pipe, projecting outwardly therefrom; a gas delivery ring through which said chimney is arranged, connected to said gas delivery pipe; a plurality of inverted burners arranged through said flange on said chimney connected to said gas delivery ring; a vertically adjustable casing having a slot therein adapted to receive said valve casing; a 10 rest for holding said casing in its elevated position, co-acting for the purpose specified.

9. In a gas lamp, the combination with a gas delivery pipe, of a gas delivery ring connected to the gas delivery pipe; a chimney 15 having an outwardly projecting flange at its lower end, arranged through said ring and secured to said delivery pipe; a valve casing at the lower end of said gas delivery pipe, projecting outwardly therefrom, connected 20 to said gas delivery pipe; a plurality of inverted burners arranged through said flange on said chimney connected to said gas delivery ring; a vertically adjustable casing having a slot therein adapted to receive said 25 valve, co-acting for the purpose specified.

10. In a gas lamp, the combination with a gas delivery pipe of a chimney connected thereto; a gas delivery ring through which said chimney is arranged, connected to said 30 gas delivery pipe; a plurality of inverted burners with separate mantles grouped about said chimney and connected to said gas delivery ring; a vertically adjustable casing arranged about said chimney and burners; a 35 rest on said delivery pipe for holding said casing in its elevated position; and a deflector slidably arranged on said gas delivery pipe, co-acting for the purpose specified.

11. In a gas lamp, the combination with a 40 gas delivery pipe of a chimney connected thereto; a gas delivery ring through which said chimney is arranged, connected to said gas delivery pipe; a plurality of inverted burners with separate mantles grouped about 45 said chimney and connected to said gas delivery ring; a vertically adjustable casing, and a deflector slidably arranged on said gas delivery pipe, co-acting for the purpose specified.

50 12. In a gas lamp, the combination with a gas delivery pipe of a chimney connected thereto; a gas delivery ring through which said chimney is arranged, connected to said gas delivery pipe; a plurality of inverted 55 burners with separate mantles grouped about said chimney, and connected to said gas delivery ring; a vertically adjustable casing arranged about said chimney and burner; a rest on said delivery pipe for holding said 60 casing in its elevated position, co-acting for the purpose specified.

13. In a gas lamp, the combination with a gas delivery pipe of a chimney connected thereto; a gas delivery ring through which

65 said chimney is arranged, connected to said gas delivery pipe; a plurality of inverted burners with separate mantles grouped about said chimney, and connected to said gas delivery ring; a vertically adjustable casing, co-acting for the purpose specified. 70

14. In a gas lamp, the combination with a depending gas supply pipe of a chimney supported thereon; an inverted burner arranged through the wall of said chimney, with its tip below the same; a deflector plate adjustably mounted on said gas supply pipe, and an outer vertically adjustable casing arranged about said chimney and burner, for the purpose specified. 75

15. In a gas lamp, the combination of a 80 gas supply pipe; a gas delivery ring connected thereto; a chimney arranged through said ring, supported by said gas supply pipe; a plurality of inverted burners with separate mantles, grouped about the said chimney; 85 and an outer casing arranged about said chimney and burners, to be vertically adjusted to afford access to the burners, for the purpose specified.

16. In a gas burner, the combination of a 90 threaded nipple; a burner tube having air openings therein threaded upon said nipple; a sleeve like valve for said openings, threaded upon said tube; a gas delivery nozzle adapted to be inserted within said burner 95 tube, threaded upon said nipple, the said openings in said burner being of such size as to permit of the removal or insertion of said nozzle therethrough, and its adjustment on said nipple; and a needle valve arranged 100 through said nipple, for the purpose specified.

17. In a gas burner, the combination of a 105 threaded nipple; a burner tube having air openings therein threaded upon said nipple; a sleeve-like valve for said openings, threaded upon said tube; a gas delivery nozzle adapted to be inserted within said burner tube, threaded upon said nipple, the said 110 openings in said burner tube being of such size as to permit of the removal or insertion of said nozzle therethrough, and its adjustment on said nipple, for the purposes specified.

18. In a gas burner, the combination of a 115 burner tube having air openings therein threaded upon said nipple; a sleeve-like valve for said openings, threaded upon said tube; and a gas delivery nozzle adapted to be inserted within said burner tube, said 120 openings in said burner tube being of such size as to permit of the insertion or removal of said nozzle therethrough and its adjustment, for the purpose specified.

19. In a gas lamp, the combination of a 125 gas delivery pipe; a chimney having an outwardly - projecting flange at its lower end connected thereto; a gas delivery ring through which said chimney is arranged connected to said gas delivery pipe; and a

plurality of inverted burners with separate mantles therefor grouped about said chimney and connected to said gas delivery ring by arms projecting inwardly therefrom, said 5 burners being arranged through the said flange of said chimney.

20. In a gas lamp, the combination of a gas supply pipe; a gas delivery ring connected thereto; a chimney arranged through 10 said ring; and a plurality of inverted burners with separate mantles therefor grouped about said chimney connected to said ring by arms projecting inwardly therefrom.

21. In a gas lamp, the combination of a 15 gas delivery pipe; a valve casing at the lower end of the said gas delivery pipe; a gas delivery ring arranged above said valve casing and connected thereto; a chimney arranged through said ring connected to 20 said gas delivery pipe; a plurality of inverted burners with separate mantles therefor grouped about said chimney and connected to said gas delivery ring; and a vertically adjustable casing arranged about said chimney 25 and burners.

22. In a gas lamp, the combination of a gas delivery pipe; a valve casing at the lower end of the said gas delivery pipe; a gas delivery ring arranged above said valve 30 casing and connected thereto; a chimney arranged through said ring connected to said gas delivery pipe; and a plurality of inverted burners with separate mantles there- 35

for grouped about said chimney and connected to said gas delivery ring. 35

23. In a gas lamp, the combination with a gas delivery pipe, of a gas delivery ring connected to the gas delivery pipe, a chimney having an outwardly projecting flange at its lower end, arranged through said ring 40 and secured to said gas delivery pipe; a valve casing at the lower end of said gas delivery pipe, projecting outwardly therefrom, connected to said gas delivery pipe; a plurality of inverted burners arranged through 45 said flange on said chimney and in operative relation to said gas delivery ring and a vertically adjustable casing having a slot therein adapted to receive said valve.

24. In a gas lamp, the combination with a 50 gas delivery pipe, of a chimney connected thereto; a gas delivery ring through which said chimney is arranged, connected to said gas delivery pipe; a plurality of inverted burners with separate mantles 55 grouped about said chimney, and in operative relation to said gas delivery ring; a vertically adjustable casing and a deflector supported on the gas supply pipe.

In witness whereof, I have hereunto set 60 my hand and seal in the presence of two witnesses.

ALFRED H. HUMPHREY. [L. s.]
